UNITED STATES PATENT OFFICE.

JOHANNES PIETER VAN GELDER, OF GRANVILLE, NEAR SYDNEY, NEW SOUTH WALES, AUSTRALIA.

MACHINE FOR GRINDING AND PULVERIZING FRIABLE SUBSTANCES.

Application filed May 24, 1924. Serial No. 715,610.

To all whom it may concern:

Be it known that I, JOHANNES PIETER VAN GELDER, subject of the King of Great Britain and Ireland, residing at 200 William Street, Granville, near Sydney, New South Wales, Australia, have invented new and useful Improvements in Machines for Grinding and Pulverizing Friable Substances, of which the following is a specification.

Mills of the type in which reduction of friable dry substances is effected by the action of revolving beaters are not practically usable when it is required to obtain a product of uniform extreme fineness. Beaters do not act effectively on small particles, and it is consequently necessary to subject products which contain granular particles to further treatment, for instance, in roller mills, or ball mills, or tube mills in order to obtain the same in uniform very fine condition. In a known type of mill using the beater principle, crusher rolls are fitted with the nip of the rolls disposed in the path of flight of granular particles which are thrown off tangentially by the beaters. These rolls operate to comminute the granular particles which reach them, and the thus comminuted material falls back into the beater casing from which it passes out through a screen. But the only granules which suffer reduction in these mills are the particles which pass through the rolls. The final product is therefore not uniformly fine in gauge. The coarsest portion of the milled product is gauged by the dimensions of the perforations in the screen, and the product is made up of a mixture of granular particles which have missed the rolls and pass through the perforations, and fines of various smaller gauges. The screen perforations must be of sufficient size to allow granular particles to pass through them freely with the finer product; if they are made too small, they are liable to be choked so that the mill would sooner or later be "flooded." The mixed gauge product thus obtained must be separated after delivery from the mill if a product of uniformly fine gauge is required. The larger particles separated from the selected fines must then be remilled if they are required to be brought to fine gauge.

The object of the present invention is to provide means whereby, in a crushing mill of the beater type, the whole of the product

may be brought to a condition of uniform extreme fineness thereby to avoid the necessity for subsequent remilling or separating, which means, when a uniform very fine product is not demanded, will be utilizable for producing a moderately finely ground product of irregular gauge.

With this object in view I have devised a mill in which the irregularly sized products of beater action, other than those of already sufficiently fine gauge are subjected to regrinding by ball action, following beater action, that is to say, the granular products of beater action are subjected in the mill to the same treatment they would sustain if they were submitted to retreatment in a ball mill after their removal from the beater mill.

The body of my mill consists of a rotatable drum-like chamber mounted for slow rotation on a horizontal axis, with a beater shaft armed with beaters mounted for fast rotation concentrically within it. Anvil bars against which the material under treatment is thrown by the beater action are mounted at their ends in the heads of this drum chamber, surrounding the beaters with clearance spaces between them. Steel or silica balls of various sizes are placed in the annular part of the drum chamber outside the belt of anvil bars; these balls locate by gravity in the lower part of the drum, covering a considerable arc of its inner surface. The beater shaft is driven at a relatively fast rate as is common practice with mills of the beater type. The drum casing is geared to the beater shaft so that it is rotated at a relatively slow rate.

The feed of lumps or pieces of dry friable material to be treated is delivered from a hopper through a chute into the beater chamber of the drum through a central vent in one head of it. The other head of the drum is vented centrally and this vent is connected into the suction opening of a centrifugal exhaust blower. The exhaust blower functions to aspirate fine products of the grinding as soon as they are released and to deliver them into a flue through which they pass to a "cyclone" or other extracting apparatus in which the fine air borne product is extracted.

The feed of coarse or irregular sized material, on entering the mill, is acted upon by the beaters in the usual way, being smashed

2
by their direct action and by their impact in flight with the anvil bars by which the beaters are surrounded. The granular material passes out between the anvil bars and 5 falls into the annular chamber and is there acted upon as in a ball mill by the balls which are operating in the bottom part of said annular chamber as the mill body rotates. The fine product is aspirated by the 10 draught produced by the exhaust blower and is carried off suspended in air and delivered through the flue to the separator.

One head of the mill body is formed with a cellular clearance space in it. The inner 15 wall of this space is perforated with holes splayed outwardly, and it is also vented into the beater chamber. This cellular space is subdivided by radial ribs to form pockets. Coarse material which is not reduced rapidly 20 by the ball action ultimately finds its way out through the perforations into the cellular pockets and is delivered back from them into the beater chamber as the drum rotates, and there again suffers treatment by 25 the beaters, and is in due course again returned to the annular ball chamber. The material which is delivered out of the mill is all sufficiently fine to be carried in suspension in the air draught created by the 30 action of the exhaust blower. The granular portions until reduced to this fine gauge remain in the mill suffering repeated grinding.

In the accompanying drawings:—

Fig. 1 is a longitudinal sectional elevation 35 through the mill;

Fig. 2 is an end sectional elevation looked at from the feed end of the mill with portion of the body shown broken away to expose the beaters and anvil bars and to show 40 the rotatable mounting of the drum body and its driving gear;

Fig. 3 is a longitudinal section through the body of the mill with the shaft and beaters removed and showing a hopper casing 45 which is attached to it when it is being operated without aspiration draught and a mixed granular and fine gauge product is delivered; and

Fig. 4 is a fragmentary sectional view 50 indicating the construction of the hopper casing which is included in Fig. 3. This view is taken on the plane of the section line 4—4 Fig. 3.

10 is the beater shaft. It is mounted for 55 rotation in standard bearings 11, and is fitted at one end of it with a driving pulley 12. 13 are beaters mounted on the central portion of the shaft 10 and located in the beater chamber of the mill body. 14 are 60 anvil bars which are disposed as a cage around the beaters on the shaft 10 so as to receive the impact of flying particles which have been thrown off by the beaters 13. 15 are collars on the shaft which cramp up 65 the beater assembly. 16 are the plates of

one head of the drum shaped body of the mill, and 17 are the plates of the peripheral or belt portion of it, which latter are of torus section. 18 is a shell casing in which the head plates 16 and the belt plates 17, 70 which are in sections of appropriate dimensions are demountably housed. The casing 18 forms at the other end of the mill an outer cheek 20 which is formed with an entry mouth 25 through which the bottom 75 end of the feed chute 24 is entered. 26 is a clearance space to allow of the rotation of the mill body relatively to the feed chute 24. 27 is a bearing collar or flange on the cheek 20, which rides on trunnion rollers 80 28, the axles of which are supported in appropriate frames 29. 19 is a ring gear fixed to the cheek 20. It meshes with a compound spur gear 37, which in turn meshes with a pinion 39 on the shaft 40 on which 85 a pulley 41 is keyed. This pulley may be driven from an independent motor or it may be belted to the beater shaft 10.

21 are perforated sectional head plates. Like the head plates 16 at the delivery end 90 of the mill body they are demountably fixed in the casing 18. The cellular clearance space between the cheek portion 20 of the casing 18 and the perforated head plates 21 is sub-divided radially to form pockets 22. 95 50 are vents at intervals surrounding the collar 23, and leading from the pockets 22 to the beater chamber of the mill. They are provided to allow granular material which finds its way outward through the perforations in the plates 21 to return to the beater chamber. 36 are balls of steel or silica or like appropriate material sized for effecting ball milling. They are placed in the annular chamber of the mill body. As the mill body rotates they run by gravity towards the bottom position therein as in a ball mill, submitting any material which may be intermixed with them to a crushing and rubbing action.

31 is an outlet sleeve in the delivery head of the mill body. It is loosely spigotted at 32 into the suction opening 33 of a centrifugal suction blower 34. The delivery mouth 35 of this blower is connected by a pipe (not 11 shown) to a "cyclone" (not shown) or other known type of separator in which the aspirated material is removed from the air current.

When withdrawal of a uniformly fine product by aspiration is not practiced, peripheral plates 44 are fitted in the mill body which plates are perforated to register with perforations 43 in the belt plates 45 of the shell 18. 46 is a screen belt of wire gauze or finely perforated sheet metal peripherally enclosing the mill body. Granular particles which pass through the perforations 42 do not pass to product when they are of too large a gauge to go through 11

the screen 46. They find their way back into the mill and there suffer regrinding by the balls. The fine gauge stuff which passes the screen 46 is collected in the casing 47, which may be a sheet iron casing completely surrounding the mill body with working clearance only, and terminating in a gravity delivery spout 52. The casing 47 is sufficiently deep on the flanges 48 to cover only the peripheral portions of the mill body, and it is mounted on a base 51 appropriately supported to locate it concentrically in relation to the mill body.

What I claim as my invention and desire 15 to secure by Letters Patent is:—

1. In a grinding mill of the type set forth, an outer mill chamber, a central beater chamber in the mill, and cellular pockets in one head of the mill body, the inner wall 20 of said pockets being perforated with holes splayed outwardly and the said inner wall being vented into the said central beater chamber.

2. A grinding mill comprising a drum-like 25 chamber mounted for rotation on a horizontal axis, means for applying rotational movement at a slow rate to said drum chamber, a horizontal shaft armed with beaters concentrically located in said drum 30 chamber, an assembly of anvil bars supported at their ends in the heads of said drum chamber and surrounding the beaters, an annular chamber surrounding the assembly of anvil bars and adapted to carry 35 a mass of grinder balls, the heads of said drum chamber being respectively provided with openings for receiving the substance to be milled and for delivery of the milled product, and means for creating air draught

of sufficient velocity through said drum chamber to aspirate and carry the milled product out of it.

3. A grinding mill comprising a drum like 45 chamber mounted for rotation on a horizontal axis, means for rotating it, a central shaft extending through said chamber and means for rapidly rotating such shaft, an assembly of beaters on said shaft within said chamber, an assembly of anvil bars disposed in parallel order longitudinally of said 50 chamber and surrounding the beaters and demountably fixed in the chamber body with clearance spaces between them adapted to permit granular particles to pass between them, a mass of grinder balls located in the 55 annular space in the chamber surrounding the anvil bar assembly, and means for removing ground products out of the mill.

4. A grinding mill comprising a drum 60 shaped body fitted with demountable liner plates and with an assembly of demountable anvil bars which bars are arranged concentrically in it to divide it into outer and inner concentric chambers, a ring gear at one 65 end of said body, roller bearing supports for said body, open hub ends in either head of said body, the one associated with a feed chute and the other with aspiration eduction means, a horizontal shaft armed with beaters disposed axially in the central chamber 70 of the mill body, a mass of grinder balls contained in the said outer chamber, and means for applying rapid rotation to the shaft and slow rotation to the mill body.

In testimony whereof I have signed my 75 name to this specification.

JOHANNES PIETER VAN GELDER.
